UNITED STATES PATENT OFFICE.

THOMAS J. LOKOMETZKI, OF MILWAUKEE, WISCONSIN.

BELL-TOLLER.

1,257,368.

Specification of Letters Patent. Patented Feb. 26, 1918.

Application filed July 18, 1917. Serial No. 181,209.

To all whom it may concern:

Be it known that I, THOMAS J. LOKOMETZKI, a citizen of the United States, and resident of Milwaukee, in the county of Milwaukee and State of Wisconsin, have invented

5 certain new and useful Improvements in Bell-Tollers; and I do hereby declare that the following is a full, clear, and exact description thereof.

10 My invention relates to new and useful improvements in bell tolling devices, particularly those which are adapted for use in church towers and belfries.

15 The principal object of the invention is to provide a simple and improved arrangement for efficiently operating chimes and the like by mechanical means.

20 It is a further general object of this invention to increase the efficiency and otherwise improve the structure of devices of this character so that they may be more inexpensively manufactured, assembled and operated.

25 With several other objects in view the invention resides in the novel features of construction, combination and arrangement of parts which will be hereinafter more particularly described, and claimed.

In the accompanying drawings:

30 Figure 1 represents a plan view of a bell tolling device constructed in accordance with my invention.

Fig. 2 is a vertical sectional view on the line 2-2 of Fig. 1.

35 Fig. 3 is a detail side elevational view of a portion of the device shown in Fig. 1.

Although in the present embodiment of my invention the device is shown arranged in plan view in the form of an isosceles triangle,

40 it is obvious that the elements constituting the invention may be arranged in any suitable configuration, the shape of the figure depending upon the number of bells which are to be used.

45 Referring more particularly to the drawings, the numeral 1 designates a plurality of supporting standards which, in the present application are all arranged equidistant from a common center and supported on a suitable platform by the bases 2. The standards are connected together at their upper and lower ends by upper and lower crank shafts 3 and 4 respectively, said standards having suitable bearings 5 and 5' provided

55 for the reception of the opposite ends of said shafts. The upper crank shafts are merely

designed to oscillate in their bearings 5, but the lower crank shafts extend entirely through their bearings 5' and are caused to revolve therein.

60

The movement of the lower crank shafts is caused by any suitable actuating means connected as at 6 to one end of one of said shafts. The other end of the last mentioned shaft and the adjacent ends of the other 65 shafts 4 are provided with intermeshing bevelled gears 7, whereby movement is transmitted to all of the lower crank shafts.

The upper crank shafts 3 each have a pair of cranks 8 projecting therefrom between which a bell or other sounding device 9 is fixed, these bells being only designed to sound when they assume certain positions. Inasmuch as the movement of the upper crank shafts 3 is merely oscillatory, it is obvious that the bells 9 will merely swing from one side to the other of said shafts as shown in the dotted and broken line positions of Fig. 2.

70 The required oscillatory movement is transmitted to the upper crank shafts from the lower crank shafts 5 by pitmen 10, which are connected respectively to long and short cranks 11 and 12, the former projecting from the shafts 3, while the latter 75 are carried by the lower shafts 4. The difference in length of the cranks 11 and 12 changes the rotary movement of the lower crank shafts to oscillatory movement in the upper crank shafts. Thus, although the 80 lower shafts are continually revolving in one direction, the bells 9 will be moved successively to opposite sides of the upper shafts 3.

75 The bells being thus arranged to sound when in different positions, it is obvious that by changing their relative positions their time of ringing with respect to each other may be varied. These changes may be carried out by changing the position of 100 the gears 7 and the shafts with which they are connected relative to each other. Any number of bells may be operated by an arrangement of this nature, the present application showing three simply for the purpose of illustration. Various other changes may be made in the form and proportion of the several parts without departing from or sacrificing any of the advantages of the invention.

105

I claim:—

110 1. In an apparatus of the class described,

a trio of shafts arranged in the form of a triangle, a connection between the adjacent ends of the shafts, a sounding device carried by each of said shafts, and means for 5 actuating the sounding devices.

2. In an apparatus of the class described, a trio of shafts arranged in the form of a triangle, a second trio of shafts also arranged as a triangle, the shafts forming the 10 sides of the second triangle being parallel to those of the first, a connection between the adjacent ends of each pair of shafts, a

sounding device on each of the first mentioned trio of shafts, a crank on each of said shafts, a pitman connecting the cranks 15 of each pair of parallel shafts, and means for revolving the second trio of shafts to operate the sounding devices.

In testimony that I claim the foregoing I have hereunto set my hand at Milwaukee, 20 in the county of Milwaukee and State of Wisconsin.

THOMAS J. LOKOMETZKI.
